UNITED STATES PATENT OFFICE.

CLARENCE G. WING, OF LAKWOOD, OHIO, ASSIGNOR TO THE SCOTT-ULLMAN COMPANY, OF CLEVELAND, OHIO, A CORPORATION OF OHIO.

DESIGN FOR AN ARM FOR LIGHTING FIXTURES OR SIMILAR ARTICLES.

Application filed December 26, 1925. Serial No. 15,873. Term of patent 3½ years.

To all whom it may concern:

Be it known that I, CLARENCE G. WING, a citizen of the United States, and a resident of Lakewood, county of Cuyahoga, and State of Ohio, have invented a new, original, and ornamental Design for an Arm for Lighting Fixtures or Similar Articles, of which the following is a specification, reference being had to the accompanying drawing, forming part thereof.

In said annexed drawing:—

The single figure there appearing is a perspective view showing my novel design of an arm for lighting fixture or similar article.

I claim:

The ornamental design for an arm for lighting fixtures or similar articles substantially as shown.
